CLAIM

The ornamental design for a cassette support base for electrophoresis gel casting, as shown and described.

DESCRIPTION

This application is related to U.S. Design patent application Ser. No. 29/545,637 filed Nov. 13, 2015, now U.S. Pat. No. D792,603, the entire contents of each of which are incorporated by reference herein.

FIG. 1 is a front perspective view of an embodiment of a cassette support base for electrophoresis gel casting showing our new design.

FIG. 2 is a back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof; and,

FIG. 9 is a front perspective view thereof showing environmental structure.

The broken lines depicting a cassette in FIG. 9 represents environmental subject matter and all other broken lines represent portions of the cassette support base that form no part of the claimed design. The broken lines and the unshaded surfaces form no part of the claimed design.
